UNITED STATES PATENT OFFICE.

ROY H. McELROY, OF DAYTON, OHIO, ASSIGNOR TO THE INTERNATIONAL CLAY MACHINERY CO., OF DAYTON, OHIO.

COMPARTMENT-KILN.

1,275,712.

Specification of Letters Patent.

Patented Aug. 13, 1918.

Application filed September 1, 1917. Serial No. 189,399.

To all whom it may concern:

Be it known that I, ROY H. McELROY, a citizen of the United States, residing at Dayton, in the county of Montgomery and State of Ohio, have invented certain new and useful Improvements in Compartment-Kilns, of which the following is a specification.

This invention relates to new and useful improvements in compartment kilns. The objects of the invention are as follows: to provide improved means for distributing the heat through the brick whereby the ware is more uniformly burned; to provide means for drawing off the waste heat from a cooling compartment whereby the heat may be used in a waste heat drier; to provide improved means for distributing the gas to the various compartments; to provide means for strengthening the support for the division walls and to provide means whereby a sufficient quantity of air is permitted to pass through the kiln to allow of the burning of a plurality of compartments at a time, and other objects as will hereinafter appear from the description and be particularly pointed out in the claims.

Referring to the accompanying drawings in general terms, Figure 1 is a top plan view of a portion of a kiln, with parts broken away, constructed in accordance with my invention. Fig. 2 is a vertical longitudinal section approximately on the line 2—2 of Fig. 3. Fig. 3 is a horizontal section, the upper portion being on the line 3^a—3^a of Fig. 2 and the lower portion being on the line 3^b—3^b of Fig. 2. Fig. 4 is a section approximately on the line 4—4 of Fig. 2. Fig. 5 is a detail elevation of one of the gas up-takes. Fig. 6 is a detailed view of a modified form of gas up-take. Fig. 7 is a detailed view showing the means for controlling the gas valves.

It is to be understood that the present invention may be applied to any well known form of kiln, constructed either in single or double battery or *en bloc*.

Referring more particularly to the drawings, 1 represents a kiln which is provided with end walls 2 and division walls 3 which support arched tops 4. The division walls 3 separate the kiln into a plurality of compartments. The side walls 2 are provided with door openings 5 which may be closed by wickets 42, and which permit access to be had to the compartments. The kiln is

provided, in each compartment, with partially perforated floors 6 upon which the ware rests.

As is well known, in kilns of this type, one or a plurality of compartments is burned at a time, and the burning is advanced after each compartment or number of compartments have been completely burned. The green ware is placed in the kiln in a compartment somewhat in advance of the compartment or compartments being burned, and the finished ware is removed from a compartment somewhat in the rear of the compartment or compartments being burned and after the ware has cooled. The heated gases from the compartments being burned are conducted to the compartments containing the green ware in advance, and the air which supports the combustion in the burning compartments is received from the ware in the cooling compartments in the rear. The heated air from the cooling compartments and the products of combustion or sulfur gases from the burning compartment are conducted from one compartment to the other by flues 7 which lie between feather walls 8 which support the floors 6. The compartments communicate with the flues 7 through the perforated floors and said flues 7 extend through the division walls 3 and discharge into the next compartment through air ports 9 behind bag walls 10. The air ports 9 are of a size which enables a sufficient quantity of air to pass therethrough to permit of a plurality of compartments being burned at a time, each burning compartment taking its quota of air as the air passes through the kiln. The air and sulfur gases after passing into the various compartments behind the bag walls 10 are deflected downwardly by the arched tops 4 through the ware and out of the compartments through the perforated floors 6. When the kiln is constructed in the form of a single battery, the flues 7 are connected by a return flue (not shown) which permits the end compartments of the kiln to communicate with each other. When the kiln is constructed in the form of a double battery or *en bloc* the opposite end compartments of each battery are connected by lateral return flues, which constructions are well known in the art. The gaseous fuel is introduced into the compartments through ports 11 in the division walls 3, the ports 11

discharging into the compartments behind the bag walls 10 and above the air ports 9. Connected to the gas ports 11 are vertical down-takes 12 which lie within the division walls 3 and communicate with gas ducts 13 at the top of the kiln. This communication is controlled by valves 14 which regulate the supply of gas to the individual ports 11. The gas ducts 13 extend to the side of the kiln and are connected to up-takes 15 located at the side of the kiln as shown in Fig. 4. This construction prevents to a great extent tar being deposited in the lateral flues 13. In Fig. 6 similar gas up-takes 15 are located within the kiln. The up-takes 15 connect with a main gas duct 16 which lies along the side of the kiln below the ground level. The main gas flue 16 extends to the end of the kiln where it is connected to a gas-producer 17 by a pipe 18. It is to be understood that when the kiln is constructed in a double battery, with two rows of compartments, or *en bloc*, the main gas duct 16 extends along both sides of the kiln. By means of this construction all of the compartments may be supplied with gas from a single or common gas producer. The supply of gas from the main gas duct 16 to the individual up-takes 15 is controlled by valves 19 operated by a chain or other flexible connections 20. To permit the valves 14 and 19 to be conveniently set when the operator is observing the condition of the fire, the flexible connections 20 are run over pulleys 21 and are extended to a point adjacent to peep holes 22 of the kiln where they may be secured by suitable hooks 23. The up-takes 15 are provided with doors 24 which permit access to be had to the interior to facilitate repair and to permit air to enter the main draft flue 16 when the tar deposits are being burned out. In the construction shown in Fig. 6 this access may be had through a cap 46. To permit of the burning out of the gas ducts 16, the gas duct at the end of the kiln is provided with a port 25 adapted to be connected to a port 26 which is connected to a stack 27 by a flue 28. When not in use the ports 25 and 26 may be covered by a cap 29, but when it is desired to burn out the flue the ports are connected by a hood 30 such as is used in connection with the main draft flue hereinafter referred to. The division walls 3 are located upon the feather walls 8, and to strengthen this support some of the flues 7—alternate flues 31 in the present instance—are stopped off, and the division walls 3 are extended to the foundation thereby providing an increased support for the walls 3. To provide for an equal distribution of the gases and air through the ware, the flues 31 which are stopped off at the division walls 3, extend only partially across the compartments, the ends adjacent to the bag walls 10 being

non-communicating and lying below the non-perforated portions 32 of the floor. This arrangement prevents a major portion of the gases escaping to the flues 7 in a path adjacent to the bag-walls 10, and compels an equal distribution of heat throughout the compartment. After the sulfur gases have passed through the pre-heating compartments in advance of the burning compartment, they are conducted out of the kiln through lateral flues 33 which lie below the floors 6 of the kiln and communicate with the flues 7 and with the flues 31 through ports 34. At one side of the kiln the lateral draft flues 33 are provided with ports 36 which are adapted to be connected, by means of a hood 30 before referred to, with ports 37 of a main draft flue 38. The main draft flue 38 is connected to the stack 27 or any other suitable draft appliance such as a fan (not shown). To equalize the pressure of the gases in the flues 7 and 31, the feather walls 8 are provided with ports 35. In addition to heating the air which supports combustion the cooling compartments may supply waste heat to be used in connection with a drier (not shown) for the green ware. In this arrangement the heated air is conducted from the compartment to a waste heat flue 39 which in the present instance lies below the main draft flue 38. The waste heat flue 39 is conducted to the waste heat drier above referred to in any approved manner. The flue 39 is provided with ports 40 which are connected to the compartments from which the waste heat is extracted by a pipe 41 which enters any one of the compartments through the wickets 42 in the door 5 thereof. The air used in waste heat drying enters the compartment through the opposite door or from an adjacent compartment. The kiln may be provided with any accepted form of water-smoking arrangement which may consist of a flue 43 arranged on top of the kiln and adapted to be connected to the various compartments by pipes 44.

The operation of the kiln is as follows: The various compartments are filled with the ware progressively and are fired successively, the ware being placed in the kiln in a compartment in front of and removed from a compartment in the rear of the compartment being fired. The ware in front is preheated by the sulfur gases or products of combustion from the burning compartment, while the air which supports combustion is preheated while passing through the cooling and previously burned compartment in the rear of the compartment being fired. The air which supports combustion enters the kiln through the doors 42 of the extreme rear cooling compartment, the wickets thereof being broken open for that purpose. The air then passes forward

through the cooling compartments through the perforated floors 6 and flues 7 which connect all of the compartments in a successive manner. When the air reaches the 5 burning compartment it is mixed with the gas (which enters the kiln through down takes 12) at the burners 11 at which point the combustion is incipient. The bag-wall 10 of the burning compartment deflects the 10 flame upward where it is directed down through the ware by the arches 4. After passing through the ware the spent or sulfur gases pass out of the burning compartment through its perforated floor where 15 they are conducted to the next and succeeding preheating compartment. When the sulfur gases reach the final preheating compartment they are conducted out of the kiln through one of the flues 33 and to a stack 20 or other draft appliance.

Having described my invention, I claim:

1. A kiln provided with a plurality of compartments, a bag wall in each compartment, perforated floors for said compartments, the side of the floors adjacent to the bag walls being less perforated than the other side, and said kiln being provided with flues which connect said compartments.

2. A kiln provided with a plurality of compartments, a bag wall arranged at the side of each compartment, a perforated floor for each compartment, said floor having non-perforated portions at one side and adjacent to the bag walls, and said kiln being 35 provided with flues which connect said compartments.

3. A kiln provided with a plurality of compartments, feather walls forming communicating flues between said compartments, division walls separating said compartments, said division walls being mounted above said feather walls and extended downwardly between the feather walls of alternate flues thereby stopping off said alternate flues, the said feather walls being of continuous form and extending through 45 the division walls.

4. A kiln provided with a plurality of

compartments, communicating flues between said compartments, a draft flue connected 50 to said communicating flues, a draft appliance connected with said draft flue, gas ports in said compartments, a gas duct connected to said gas ports, and a hood connecting said gas duct to said draft appliance. 55

5. A kiln provided with a plurality of compartments, communicating flues between said compartments, a main draft flue connected with said communicating flues, a 60 draft appliance connected with said main draft flue, gas ports in said compartments, a gas duct connected with said gas ports, said draft appliance and said gas duct being provided with ports, and a hood adapted 65 to connect said last named ports.

6. A kiln provided with division walls forming a plurality of compartments, gas ports for said compartments, gas down-takes in said division walls and connected 70 with said ports, a main gas duct connected to said down-takes, communicating flues between said compartments, a main draft flue connected to said communicating flues, a draft appliance for said main draft flue, 75 a hood adapted to connect said gas duct with said draft appliance, and a water-smoking flue common to and adapted to be connected with said compartments.

7. A kiln provided with a plurality of 80 compartments, gas ports for said compartments, gas up-takes located at the side of the kiln and connected to said gas ports, a main gas duct connected to said gas up-takes, and communicating flues between said 85 compartments.

8. A kiln provided with a plurality of compartments, gas ports for said compartments, gas up-takes located at the side of and exterior to the kiln and connected with 90 said gas ports, a main gas duct connected to said gas up-takes, and communicating flues between said compartments.

In testimony whereof I affix my signature.

ROY H. McELROY.
